A. H. KLATT

AUXILIARY SEAT FOR AUTOMOBILES

Filed Sept. 8, 1922

Inventor
Albert H. Klatt
by Hazard & Miller
ATTORNEYS

UNITED STATES PATENT OFFICE.

ALBERT H. KLATT, OF LOS ANGELES, CALIFORNIA.

AUXILIARY SEAT FOR AUTOMOBILES.

Application filed September 8, 1922. Serial No. 586,831.

To all whom it may concern:

Be it known that I, ALBERT H. KLATT, a citizen of the United States, residing at Los Angeles, in the county of Los Angeles and 5 State of California, have invented new and useful Improvements in Auxiliary Seats for Automobiles, of which the following is a specification.

My invention relates to auxiliary seats for 10 automobiles, and a purpose of my invention is the provision of an auxiliary seat which includes a receptacle adapted for storing articles of different characters and has an enclosure for a portable toilet.

15 Although I will describe only one form of combined seat and storage receptacle, and will point out the novel features thereof in claims, it is to be understood that various changes and modifications may be made 20 without departing from the spirit of the invention and the spirit and scope of the appended claims.

In the accompanying drawings,

25 Figure 1 is a vertical sectional view of the combined seat and receptacle embodying my invention;

Figure 2 is a perspective view of the seat and receptacle shown in Figure 1 in closed position;

30 Figure 3 is a view similar to Figure 2, showing the seat in open position.

Similar reference characters refer to similar parts in each of the several views.

Referring specifically to the drawings, my 35 invention, in its present embodiment, comprises a storage receptacle designated at 15, and which in the present instance is shown as being of rectangular formation, with its upper side open to allow of the introduction 40 or removal of articles to and from the receptacle. This receptacle is formed of any suitable material, preferably wood, and may not be covered with a cloth or other suitable fabric.

45 The receptacle 15 constitutes a standard or support for the auxiliary seat which is shown as comprising the seat portion 16 and a back portion 17. The seat portion 16 includes a padded portion 16^a secured to a panel 16^b which constitutes a cover for the open top of the receptacle 15. This panel 16^b is hingedly secured to the receptacle as indicated at 18, so as to allow of the cover occupying closed position as shown in Fig. 50 2, or open position as shown in Fig. 3. In the closed position of the cover or panel, it

cooperates with the receptacle to provide a support for the seat portion 16, and when in open position it permits access to the interior of the receptacle 15. The panel 16^b 60 is adapted to be limited in its open position by means of a bracket 19 secured to the panel and a connecting bar 20 slotted to receive a screw or other fastening member 21 secured to the inner side of the receptacle 65 15 and operating to limit the upward movement of the bar 20, so that the open position of the panel 16^b is defined.

The back portion 17 is constructed in any suitable manner, and preferably in the manner shown in Fig. 1, where it will be seen that a rectangular metallic frame 22 is provided and which is spanned by a sheet of fabric 23. The frame 22 is hingedly supported upon the seat portion 16 so as to occupy a folded position, as shown in Fig. 3, or an extended position, as shown in Fig. 2, the means of connection being such as to limit the extended position to a substantially vertical one.

70 The rear wall of the receptacle is provided with an opening 29 controlled by a door 30 hingedly supported upon the wall as indicated at 31. This opening is provided for the purpose of allowing the insertion or 75 removal of a receptacle 32 into or out of the receptacle 15. The receptacle 32 is adapted to be properly positioned with relation to the lower end of the spout 33 by means of a U-shaped rib 34 secured to the inner side 80 of the bottom of the receptacle 15. The spout 33 is sustained in vertical position within the receptacle by means of a flange 35 formed integrally with the spout and engaging the upper side of a rectangular rib 95 36. A seat portion 37 is superimposed upon the flange 35 but removably associated therewith so as to allow the removal of the spout for cleaning purposes.

85 A lock 38 may be provided upon the receptacle 15 at its upper edge so as to secure the cover panel 16^b in closed position upon the receptacle.

90 In practice, the auxiliary seat and receptacle are adapted to be placed upon the floor 105 of an automobile to take the place of the ordinary auxiliary seat, and it will be seen that in applied position the receptacle 15 constitutes a standard for supporting the seat in elevated position with relation to 110 the floor of the vehicle. At the same time, the receptacle 15 can be employed to com-

pletely conceal a portable toilet or a food container. The invention is obviously not limited for use within an automobile, but it can also be used upon the ground, as when 5 picnicing.

I claim as my invention:

1. In combination, a receptacle having an open top and an opening in one side thereof, a door controlling said opening, a receptacle 10 within the first receptacle, a rib within the receptacle adjacent the open top thereof, a spout including a flange engaging said rib, a seat member engaging said flange and supported on said rib, and a seat including a 15 seat portion hingedly sustained upon the first receptacle and normally closing the top of said receptacle and a back portion hingedly supported upon the seat portion.

2. In combination, a receptacle having an 20 open top and an opening in one side thereof, a door controlling said opening, a receptacle within the first receptacle, a positioning rib on the bottom of the first receptacle which is adapted to be engaged by the second re- 25 ceptacle, a second rib within the receptacle adjacent the open top thereof, a spout including a flange engaging said second rib, a seat member engaging said flange and supported on said rib, and a seat including a

seat portion hingedly sustained upon the 30 first receptacle and normally closing the top of said receptacle and a back portion hingedly supported upon the seat portion.

3. An auxiliary seat comprising a rectangular receptacle having a closed bottom and 35 an open top and an opening in one side, a door for said opening, a positioning rib upon the bottom at the opposite side from the door, a second receptacle removably mounted through the door against the positioning rib, a second rib within the first receptacle adjacent the top thereof, a spout discharging into the second receptacle and including a flange resting upon said second 40 rib, an open seat member engaging said flange and supported on said second rib, a seat construction including a seat proper 45 hingedly sustained upon the first receptacle and normally closing the top of said receptacle, and a back hingedly supported upon 50 the seat proper and adapted to swing to a vertical position and to be held from swinging backwardly beyond the vertical position.

In testimony whereof I have signed my 55 name to this specification.

ALBERT H. KLATT.
